US00D872645S

(12) United States Design Patent (10) Patent No.: US D872,645 S
Lachyani Abiri et al. (45) Date of Patent: * Jan. 14, 2020

(54) UNICORN FIGURE

(71) Applicants: Osnat Lachyani Abiri, Pardes Hanna (IL); Raz Lachyani Abiri, Pardes Hanna (IL)

(72) Inventors: Osnat Lachyani Abiri, Pardes Hanna (IL); Raz Lachyani Abiri, Pardes Hanna (IL)

() Term: 15 Years

(21) Appl. No.: 29/668,704

(22) Filed: Nov. 1, 2018

(51) LOC (12) Cl. 11-02

(52) U.S. Cl.

USPC D11/159; D21/620

(58) Field of Classification Search

USPC D11/162, 238, 239, 82, 100, 131, 137, D11/184, 157, 158, 159, 44, 49, 57; D21/606, 416, 429, 576, 585, 587, 591, D21/620, 626, 614, 619, 832; D26/94, D26/98, 17, 18; D19/34.3, 34.4; D20/29-31; 446/313, 268; 362/124; 428/28
